Attorney

UNITED STATES PATENT OFFICE.

HERMAN M. BERDAHL, OF COLTON, SOUTH DAKOTA.

OIL-CAN.

1,307,478.

Specification of Letters Patent. Patented June 24, 1919.

Application filed April 7, 1919. Serial No. 288,067.

To all whom it may concern:

Be it known that I, HERMAN M. BERDAHL, a citizen of the United States, residing at Colton, in the county of Minnehaha and State of South Dakota, have invented certain new and useful Improvements in Oil-Cans, of which the following is a specification, reference being had to the accompanying drawings.

- 10 This invention relates to certain improvements in oil cans and has relation more particularly to a device of this general character embodying a forced feed, and it is an object of the invention to provide a device 15 of this general character having novel and improved means whereby a force pump may be suitably arranged within the can proper and operating to cause an effective flow of oil through the spout.
- 20 It is also an object of the invention to provide a device of this general character having novel and improved means whereby the pump is readily applied within or removed from the can and wherein the pump 25 includes an operating member extending exteriorly of the can and in a position to be engaged by a digit, preferably the thumb, of the hand engaged with the can.

The invention consists in the details of 30 construction and in the combination and arrangement of the several parts of my improved oil can whereby certain important advantages are attained and the device rendered simpler, less expensive and otherwise 35 more convenient and advantageous for use, as will be hereinafter more fully set forth.

The novel features of my invention will 40 hereinafter be definitely claimed.

In order that my invention may be the 45 better understood, I will now proceed to describe the same with reference to the accompanying drawings, wherein:

Figure 1 is a vertical sectional view taken 50 through a can constructed in accordance 45 with an embodiment of my invention, certain of the parts being in elevation, and

Fig. 2 is a view in top plan of the cap as 55 herein included.

As disclosed in the accompanying drawings, B denotes the body of my improved can of a predetermined capacity and having 60 extending outwardly from the side wall thereof the handle or hand grasp H. The central portion of the body B at its top is 65 provided with an opening 1 defined by the

outstanding annular flange 2 upon which is 60 adapted to be threaded or otherwise engaged the spout S to be hereinafter more particularly referred to. The top of the body B at one side of the opening 1 is provided with a second opening 3 defined by the outstanding annular flange 4 with which is engaged a holding cap 5.

C denotes an elongated cylinder insertible 65 through the opening 3 on an angle of substantially 45 degrees relative to the bottom of the body B, and of a length to have its inner or inserted end portion terminate in close proximity to the bottom of the body B when the cylinder is in working position. 70 The outer end portion of the cylinder C is provided with an outstanding annular flange 6 contacting with the outer edge of the flange 4 and with which the cap 5 engages for holding the cylinder C in applied position. 75

The inner or inserted end portion of the cylinder C is reduced as indicated at 7 and said reduced portion has its outer or free extremity provided with a valve seat 8 with 80 which coacts the ball valve 9 arranged within the reduced portion 7 and operating to close the inner or induction end of the cylinder C.

In communication with the reduced portion 7 of the cylinder C is a branch 10 of a length to terminate in a plane substantially flush with the outer wall of the cylinder C proper, so that said cylinder C may be readily inserted or withdrawn through the opening 3. 85

11 denotes a feed tube insertible through the opening 1 and adapted to have its inner end portion threaded upon or otherwise coupled to the branch 10 and said inner or 90 inserted end portion of the tube 11 is provided with an internal valve seat 12 with which coacts the ball valve 14 or the like.

The movement of the valve 14 away from its seat 11 is limited by the inwardly directed pins 15 carried by the feed tube 11 and the movement of the valve 9 away from its seat 8 is limited by the inwardly directed pins 16 carried by the extended portion 7 of the cylinder C outwardly of the branch 10. 100

The outer end portion of the feed tube 11 is defined by the outstanding and laterally directed annular flange 17 which rests upon the outer edge of the flange 2 so that the coupling 18 at the inner end of the spout S 110

and engageable with the flange 2 serves to effectively support the outer end portion of the tube 11 in working position.

It is to be noted that the valve seats 8 and 12 are arranged in close proximity so that substantially immediate priming or forcing of oil or the like upwardly through the tube 11 occurs upon the downward stroke of the piston P within the cylinder C. The piston 10 P is carried by the inner end of a rod or plunger 19 extending exteriorly of the cylinder C through the removable head 20 closing the outer end of the cylinder C. The exterior extremity of the plunger or rod 15 19 is provided with a knob 21 or the like which is adapted to be engaged by the thumb or other digit of a hand grasping the handle H in order to impart the desired working stroke to the piston P. The piston P 20 is adapted to be automatically returned through the medium of the expansible member 22, herein disclosed as a coil spring, interposed between the inner face of the piston P and the annular shoulder 23 afforded at 25 the inner end of the reduced portion 7 of the cylinder C.

The spout S has disposed longitudinally therethrough a feed pipe 24 which, when the spout is in applied position, communicates 30 or registers with the feed pipe 11 so that the desired flow of oil or the like may be had through the spout S. By this arrangement, the spout S proper serves as a guard or protection for the feed pipe 24 as the 35 spout proper prevents damage to the pipe 24 during a working operation.

The pipe 24 extends beyond the outer end of the spout S and engaged with such extended portion is the tip T preferably ar- 40 ranged on a longitudinal curvature.

It is also to be understood that the cap 5 is provided with a central opening to permit the insertion therethrough of the cylinder C.

From the foregoing description, it is 45 thought to be obvious that an oil can constructed in accordance with my invention is particularly well adapted for use by reason of the convenience and facility with which it may be assembled and operated, and 50 it will also be obvious that my invention is susceptible of some change and modification without departing from the principles and spirit thereof and for this reason I do not wish to be understood as limiting myself to

the precise arrangement and formation of 55 the several parts herein shown in carrying out my invention in practice except as hereinafter claimed.

I claim:

1. A can of the class described comprising 60 a body provided with a pair of spaced openings in the upper end portion thereof, each of said openings being defined by an out- standing flange, a cylinder insertible through one of the openings, means coacting with 65 said cylinder and the flange of said opening for securing the cylinder in applied position, the inserted end of the cylinder being provided with a valve controlled opening, a feed pipe detachably engaged with the in- 70 serted end portion of the cylinder, the op- posite end portion of the feed pipe being provided with a flange engaging the outer edge of the flange of the second opening, a spout engageable with the flange of the 75 second opening and coacting with the flange of the feed pipe to secure said end portion of the feed pipe, and a piston work- ing within the cylinder.

2. A can of the class described comprising 80 a body provided with a pair of spaced openings in the upper end portion thereof, each of said openings being defined by an out- standing flange, a cylinder insertible through one of the openings, means coacting with 85 said cylinder and the flange of said opening for securing the cylinder in applied position, the inserted end of the cylinder being provided with a valve controlled opening, a feed pipe detachably engaged 90 with the inserted end portion of the cylin- der, the opposite end portion of the feed pipe being provided with a flange engaging the outer edge of the flange of the second opening, a spout engageable with the flange of the 95 second opening and coacting with the flange of the feed pipe to secure said end portion of the feed pipe, and a piston work- ing within the cylinder, said feed pipe being provided with a controlling valve adjacent 100 its connection with the cylinder.

In testimony whereof I hereunto affix my signature in the presence of two witnesses.

HERMAN M. BERDAHL.

Witnesses:

C. A. WOOD,
E. WAGGONER.
